UNITED STATES PATENT OFFICE.

GEORGE M. DOERSCH, OF ANTIGO, WISCONSIN, ASSIGNOR OF ONE-FOURTH TO JOHN C. LEWIS, OF ANTIGO, WISCONSIN.

FUSE-SUPPORT.

1,114,594.

Specification of Letters Patent. Patented Oct. 20, 1914.

Application filed August 21, 1913. Serial No. 785,854.

To all whom it may concern:

Be it known that I, GEORGE M. DOERSCH, a citizen of the United States, residing at Antigo, Langlade county, and State of Wisconsin, have invented and discovered certain new and useful Improvements in Fuse-Supports, of which the following is a specification.

My said invention consists in an improved construction of clip or device for holding a fuse and cap for exploding dynamite cartridges, whereby a device of the character described is provided which is inexpensive in structure, may be quickly and easily used, will be efficient in service, and by its use the crimping and pinching of the cap is avoided and the danger in operation largely obviated, all as will be hereinafter more fully described and claimed.

Referring to the accompanying drawing which is made a part hereof, and on which similar reference characters indicate similar parts, Figure 1 is a perspective view of one of my improved clips separately, and Fig. 2 a similar view showing the clip in use.

In said drawings the portions marked A represent the dynamite cartridge, B the fuse, and C the supporting clip.

The dynamite cartridge A is of a usual form and the fuse B with cap (not shown) on its lower end is inserted in an aperture in one end thereof. The clip C is a metal bar, preferably wire, having a right-angle arm 10 formed with a point adapted to be inserted in one side of the cartridge and its upper end has a right-angle arm 11 bent to form a loop or hook 12 adapted to embrace the fuse B at a point adjacent to the upper end of the cartridge.

In use the fuse and cap are inserted in the cartridge A in the usual manner. The

pointed end of arm 10 of the clip is inserted in the side of the cartridge and the loop formed by the parts 11 and 12 are hooked around the fuse B and pinched or crimped against its sides to support it in position and hold both the fuse and the cap in place, thus avoiding any crimping or pinching of the cap on the lower end of said fuse and obviating the danger of such operation.

Having thus fully described my said invention, what I claim as new and desire to secure by Letters Patent is:

1. A fuse holder for supporting the fuses in the ends of dynamite cartridges comprising a clip formed of a single piece of material, one end of which is turned at right angles with the main body of the clip and formed pointed and adapted to be inserted in the side of the cartridge, and the other end of which is turned at right angles with said main body and substantially parallel with said point and formed with a part adapted to embrace and support the fuse, substantially as set forth.

2. A fuse holder for supporting the fuses in the ends of dynamite cartridges, which consists of a single piece of wire with one end bent at right angles to its main portion and adapted to be inserted in the side of the cartridge, and its other end bent at right angles to the main portion to extend across the top of the cartridge and formed with a loop adapted to embrace and support the fuse, substantially as set forth.

In witness whereof, I have hereunto set my hand and seal at Antigo, Wisconsin, this 19th day of August, A. D. nineteen hundred and thirteen.

GEORGE M. DOERSCH. [L.S.]
